US00D952245S

(12) **United States Design Patent** (10) **Patent No.:** **US D952,245 S**
Farrow (45) **Date of Patent:** **** May 17, 2022**

(54) **CHARGING UNIT FOR AN AEROSOL GENERATING DEVICE**

- (71) Applicant: **Philip Morris Products S.A.**, Neuchâtel (CH)
- (72) Inventor: **Alexander Farrow**, Pleasant Hill, CA (US)
- (73) Assignee: **Philip Morris Products S.A.**, Neuchâtel (CH)

(**) Term: **15 Years**

(21) Appl. No.: **29/764,288**

(22) Filed: **Dec. 29, 2020**

(30) **Foreign Application Priority Data**

(57) **CLAIM**

The ornamental design for a charging unit for an aerosol generating device, as shown and described.

DESCRIPTION

FIG. 1 is a front, top, and right side perspective view of a first embodiment of a charging unit for an aerosol generating device showing the new design.

FIG. 2 is a front elevational view thereof.

FIG. 3 is a rear elevational view thereof.

FIG. 4 is a top plan view thereof.

(Continued)

FIG. 5 is a bottom plan view thereof.

FIG. 6 is a right side elevational view thereof; and,

FIG. 7 is a left side elevational view thereof.

1 Claim, 7 Drawing Sheets
